(21) Appl. No.: **29/330,554**

The ornamental design for an air hammer with quick change chuck, as shown and described.

(22) Filed: **Jan. 9, 2009**

DESCRIPTION

(51) **LOC (9) Cl.** **08-05**

FIG. 1 is a front perspective view of the air hammer with quick change chuck according to a first embodiment of the present design.

(52) **U.S. Cl.** **D8/68**

FIG. 2 is a right side elevation view of the air hammer with quick change chuck as shown in FIG. 1;

(58) **Field of Classification Search** D8/61-69;

FIG. 3 is a left side elevation view of the air hammer with quick change chuck as shown in FIG. 1;

81/57.11, 429, 464, 465, 466, 469, 489; 173/13, 173/169, 178, 213, 217; 227/8, 114, 120, 227/130, 136, 142; 310/50; 408/20, 124, 408/125, 234, 241 R; 451/358

FIG. 4 is a top side plan view of the air hammer with quick change chuck as shown in FIG. 1;

See application file for complete search history.

FIG. 5 is a bottom side plan view of the air hammer with quick change chuck as shown in FIG. 1;

(56) **References Cited**

FIG. 6 is a front elevation view of the air hammer with quick change chuck as shown in FIG. 1; and,

U.S. PATENT DOCUMENTS

FIG. 7 is a rear elevation view of the air hammer with quick change chuck as shown in FIG. 1.
